FIG. XI.

UNITED STATES PATENT OFFICE

FRANCIS H. BROWN, OF RIDLEY PARK TOWNSHIP, DELAWARE COUNTY, PENNSYLVANIA

MEANS FOR BURNING COMBUSTIBLES WITH IMPROVED CALORIFIC EFFICIENCY

Application filed October 11, 1932. Serial No. 140,975.

This invention relates in its generic aspect to the burning of combustibles, while it has more particular reference to the combustion of fluent fuels such as oil, gas, powdered coals in suspension; and compositions, compounds or combinations of any such fuels.

Specifically the present invention provides a novel method of attaining a new or finely atomized condition for combustibles, and may include reciprocative and high-speed rotative tip members with associated means whereby such state of atomization is effected. Hereinafter the improved state of atomization attained by my invention will be qualified as "superfine", or such analogous expression, in order to better distinguish the same over known methods and means adapted to the same ends.

It is to be noted that my novel means for establishing and varying, or maintaining stream formation, stream bulk and directional flow, of a combustible and its atomizing agencies, as well as the angular intersecting or relative "shear" of the currents or streams, all center at one point. Furthermore, each and every one of the stated factors is variable as desired by adjusting a single means or part, or each may be varied independently of the others; such adjustments being accomplished manually or automatically in response to variations in any one or more of said factors; or, any combination of them, incident to—or resultant from—the practical operation of the embodiment of this invention hereinafter described, as well as the particular conditions of combustion prevailing.

Again, the manner of controlling or regulating the draft and other factors, incidental to the disclosed embodiments of this invention, is purely exemplary of how my invention may be successfully reduced to practice.

For a clearer understanding of the invention I will now describe it in detail with reference to the accompanying sheets of drawings, while the subjoined claims serve to indicate those features alleged as novel in the art.

In the drawings:—

Fig. I is a top plan view of a liquid—pow-

dered or gaseous—fuel burner embodying one typical assemblage of the present invention, which is effective to successfully operate in accordance with the novel method involved. Fig. Ia is a longitudinal section, to a reduced scale, of the right hand portion of Fig. I.

Fig. II is a side elevation with the burner nozzle in axial section to better disclose certain underlying details.

Fig. III is a plan section of a modified assemblage of the burner and also showing a convenient power means for operating a rotatable element in the burner.

Fig. IV is an end view of the nozzle looking to the right hand of Fig. III, and showing certain gears by dot-and-dash lines with associated arrows to indicate a possible direction of rotation for the respective gears.

Fig. V is an individual shifter means hereinafter fully explained.

Fig. VI is a similar detail view of a compound shifter means later on specifically described.

Fig. VII is an elevation of a slightly modified assemblage of the invention with parts in section for a clearer illustration of certain underlying details.

Fig. VIII and IX are detailed sectional views of a slightly different form of burner tip, the latter being taken on the plane designated IX—IX in Fig. VIII.

Figs. X and XI are a sectional view and an axial section, respectively, of another form of burner tip embodying this invention, the former being taken approximately on the plane indicated by the arrows X—X in the latter.

Figs. XII and XIII are an end view and an axial section, respectively, of an alternative form of the present invention; and,

Figs. XIV and XV are sectional illustrations of a still further embodiment of the present improvements.

In all views of the drawings like or corresponding parts are uniformly distinguished by the same reference characters.

Referring more specifically to Figs. I, Ia and II, of the accompanying drawings, my novel type of fuel feed and atomizing burner

is comprehensively designated by the numeral 1, and it comprises a barrel portion 2 with an integral—or attached—head 3 having fuel feed and atomizing medium connections 4, 5, respectively; or vice versa. These connections 4, 5 are fitted with flow controls in the form of plug valves 6, 7, respectively, the stems whereof have attached crank members or manipulating keys 8, 9, the angled portions whereof are in the form of slotted sectors 10, 11. Adjustable relative to the sectors 10, 11, are slide blocks 12, 13, having composite connecting-rods 14, 15 pivoted on a common center pin 16 passed through the outer end of a crank 17, whose other end conventionally laps an eccentric 18, on a shaft 19 journaled in bearings 20, provided for the purpose, in the spaced extensions 21 of the aforesaid burner head 3. Intermediate their ends the connecting-rods 14, 15 are fitted with turnbuckles 22, whereby they are longitudinally adjustable for a purpose later on explained. Splined on the upper end of the shaft 19 is a pointer 23 adapted to traverse a graduated dial 24 which is marked to indicate burner tip variations, and said dial is conveniently supported by an angled portion 25 rigidly secured to the adjacent head extension 21.

Referring again to the barrel portion 2 of the burner 1, the same includes inner coaxial pipes 26, 27 each of which is longitudinally movable relative to the other—as well as with respect to the barrel 2—through the medium of means, later on fully described. The barrel portion 2, as hereinbefore noted, is conveniently screw-threaded at its inner end into the head 3, while the outer end thereof is fitted with a removable cupped nozzle 28, counter-bored at 29 to seat the perforate tip plate 30, that is held in place by a flanged annulus or angular-section locking collar 31. Similarly the intermediate pipe 26 is fitted with a removable cup piece 32 and a cap member 33; said pipe and cup piece being of smaller diameters than the barrel 2 and nozzle 28, respectively, to afford a clearance 34 for flow of the fluent fuel. On the other hand, the innermost pipe 27 is of a diameter to provide a surrounding clearance 35 relative to the intermediate pipe 26 for flow of the atomizer medium, but the cupped end 36 thereof is of a diameter slightly less than that of the cup piece 32, with provision of a slight clearance 37. The flat closure wall 38 of the cupped end 36 is bored and screw-threaded at intervals to receive a pilot nipple 39 and a series of surrounding jet tips 40, while it is to be particularly noted that the tip plate 30 and the perforate end wall of the cap member 33 never actually contact so that a very small quantity of atomized mixture may be supplied about the pilot nipple 39 when the device is “shut down.” As best appreciated

from Fig. IV, the pilot nipple 39 is located axially central of the burner 1, whereas the surrounding tips 40 are arranged in vertical or horizontal rows and in relatively staggered relation. It will be seen in Figs. II and III that the pilot nipple 39 inwardly converges at its outer end, while the surrounding tips 40 are outwardly flared; and that both said nipple and tips pass through apertures in the cap member 33 and tip plate 30. Furthermore, it is particularly noteworthy, that when the tips 40 approach the position shown in Fig. II, the pilot nipple 39 is retracted from the tip plate 30 and perforate end wall of the cap member 33 with provision of a clearance 39'; and vice versa. In other words when the burner 1 is “shut down,” as shown in Fig. II, fuel is discharged by way of the clearance 39' about the pilot nipple 39 with combustion-supporting atmospheric air discharging through the latter for “intersecting-shear” therewith, in sufficient quantity to maintain a small pilot flame, as will be readily understood by those acquainted with the art; or, when the device is “shut down” the tips 40 act as valves to close the orifices in the plate 30 and cap member 33.

Referring again to the means for moving the pipes 26, 27 longitudinally, it is firstly to be observed that the former projects through the burner head 3 by way of an appropriate gland 41, while it is fitted at its outer end with a gland device 42, having diametrically opposed pintles 43, Fig. II. Pivoted to the pintles 43 are composite connecting-rods 44—with interfitting turnbuckles 45—in turn coupled to eccentrics 46 on the shaft 19, hereinbefore referred to. Similarly, the open outer end of the innermost tube 27 projects through and beyond the gland device 42 and is fitted with a pivoted yoke 47, held thereto by pintles 43' having a composite connecting-rod 48, and turnbuckle 49, co-ordinated with the shaft 19 through the medium of an eccentric 50. Incidentally, the end of the tube 27 is provided with cut outs 69, for ingress of atmospheric air; while attention is directed to the fact that the center pin 16 for the connecting rods 14, 15 is co-operative with a suitable guide 51—Fig. II—conveniently secured to the outer face of the adjacent burner head extension 21, so that its movement aligns with the longitudinal axis of the burner 1. Clamp nuts 52 are provided in connection with the several turnbuckles 22, 45 and 49, to lock all the respective adjustments of the entire burner 1 in varied relation, as required; while said turnbuckles 22, 45 and 49, serve to effect initial adjustment of the burner so that, when the eccentric shaft 19 is turned to “shut down”, the tips 40 effectively close their associated oil and air delivery orifices in the plate 30 and cap member 33, as well as for effecting proper adjustments

whereby the nipple 39 and the valves 6, 7 are so positioned that a pilot flame at said nipple results.

Assuming that the several eccentrics 18, 46 and 50, have been "initially set" for a predetermined zero condition or fuel discharge at the tip plate 30 to keep a pilot flame at the nipple 39 alight, when the burner 1 is "shut down" it will be apparent that by turning 10 the shaft 19 through the medium of a hand wheel 19', Fig. II for example, and thereby moving the pointer 23 over the graduated dial 24, I am enabled to minutely change the form and character of the atomized combustible fuel discharge exteriorly at the jet tips 40 through the apertures in the plate 30 and end wall of the cap member 33 to meet all variations in load and character of fuel or fuel condition, as well as to accommodate other 20 conditions incident to normal operation. On the other hand, variation in the relative composition of the combustible discharge at the burner end is readily effected by adjustments in the lengths of the several connecting rods 25 14, 15, 44 and 48; whereby changes in the respective pressures of the fuel and its atomizing agent—as well as their proportion and direction of intersection at the tips 40—are minutely accomplished.

Assuming the respective eccentrics 46, 50 have been initially positioned or "set" relative to the eccentric 18—and its actuated connections—to give a desired predetermined 30 flow of atomizing agent and fuel from the control valves 9, 8, respectively, into the clearances 34 and 35, for a specific discharge condition at the jet tips 40, with the pointer 23 at a zero indication on the dial 24, it will be evident that the controls 6 and 7 are consequently adjusted to accommodate the requisite flows of fuel and atomizing medium for such condition. In accordance with the specific disclosure the flow of fuel, is via the clearance 34, between the tip plate 30 and end 40 wall of the cap member 33 to the outlet perforations in said tip plate. Flow of the atomizer medium is via the clearances 35, 37, through the perforations in the end wall of the cap member 33 and outlet orifices in the tip plate 30: while flow of atmospheric air is via the tube 27, jet tips 40, and pilot nipple 39. Atmospheric air for ignition and support of combustion when the device is in operation is drawn by way of the cut outs 69 into the pipe 27 under the general action of the burner in an obvious manner. Control of the discharge condition at the burner end to regulate or vary the flow of oil and atomizer medium, in other words, the rate of combustion, during operation of the burner, either 55 manually or automatically, is effected by simply turning the eccentric 19 carrying the pointer 23, the necessary number of degrees over the dial 24 in the proper direction—to 60 effect opening or substantial closure of the re-

spective controls 6, 7. Such movement of the pointer 23, through the connections hereinbefore described under the action of the eccentric 50, effects an outward movement of the burner tips 40, and the pilot nipple 39, whereas the fuel stream formation cap or member 33 is retracted relative to the tip plate 30, incident to a reverse action upon the part of the eccentric 46 or vice versa. Thus it will be apparent an operator can easily adjust the burner, or a co-ordinate series of such burner devices, to start combustion in a furnace—for example—equipped therewith to a maximum calorific efficiency. On the other hand, it is equally obvious that the burner, or burners, can be readily adjusted to accommodate any desired changes of fire effect from the predetermined "set" condition by simple movements of the eccentric shaft 19 through the medium of the handle 19' carrying the pointer 23.

Referring now to Fig. III, all elements having corresponding parts in the preceding explanatory matter are similarly designated, and only those structural features varying therefrom will now be explained in detail to avoid repetitive description. The fundamental difference, however, in this form of my invention involves an axial conduit 53, which—it will be seen—constitutes a continuation of the pilot nipple 39, and means whereby the same—as well as the jet tips 40—are all rotatable in unison. Attention is firstly directed to the pilot nipple 39 which is slightly inwardly-converged with its exterior surface coned correspondingly to the flare of the jet tips 40, to provide the clearance 39' as aforesaid. The conduit 53, where it projects through the yoke 47 is fitted with collars 54 which prevent longitudinal movement relative to said yoke, while permitting free rotation thereof. At its free end the conduit 53 has splined thereon a pulley 55, co-ordinated by a belt drive 56 with an appropriate motor 57, conveniently mounted on a lateral projection 58 of one of the burner head extensions 21. To the extreme outer end of the conduit 53 I secure one element of a composite connecting-rod 59 having an intermediate turnbuckle 60; whereas the other element of said rod is fashioned to afford universal connection at 61 with a head 62 on an eccentric sleeve 63. This sleeve 63 is mounted on the shaft 19, aforesaid, with provision for independent adjustment through the medium of a grasp 64—Fig. V—so that the conduit 53, as well as the inner pipe 27, may be simultaneously moved longitudinally, for a purpose hereinbefore set forth.

Splined—or otherwise secured—on the inner end of the conduit 53 is a pinion 65 functional to co-ordinate correspondingly toothed gears 66, one of which is fitted to the inner end of each rotatively mounted jet tip 40 in the center vertical row, as viewed in

Fig. IV; while similar gears 66' coordinate the flanking rows in the view referred to. It is also obvious that the bores of the tips 40 extend through the associated gears 66 and 66'. In order to rotate all of said tips 40 and the pilot nipple 39, a relatively larger stepped-gear 65' on the conduit 53 meshes correspondingly-toothed and similarly stepped gears 66'' associated with one of the gears 66' in each flanking vertical row beforementioned, whereby all of the gears are coordinated for operation in unison as graphically indicated by the arrows on Fig. IV.

In Fig. VI, I have illustrated combined means effective to independently vary the relative longitudinal relation of the intermediate pipe 26, as well as the coupled pipe 27 and conduit 53. This means differs from that previously described by provision of a handle member 67 secured to the outer end of the shaft 19, by a set screw 68—for example—whereby said shaft and the eccentrics 46 thereon may be relatively turned with respect to the eccentric sleeve 63. Atmospheric air to support combustion at the burner tip, as before set forth, is supplied to the pilot nozzle 39 and jet tips 40 by way of the pipe 27 through cut outs 69, Figs. II and III, at the outer end thereof adjoining the pivoted yoke 47. The rotary conduit 53 is perforated locally at 70 so that a portion of the atmospheric air is diverted directly to the pilot nipple 39, while that flowing through the tube 27 commingles with atomizing medium flowing about the cupped end 36 from the clearance 35 for distribution about the jet tips 40, as will be readily appreciated from an examination of the drawings.

The initial setting of this type of my invention, as well as the general flow and control of the combustible constituents, in general respects, corresponds with that set forth in connection with the disclosure in Figs. I and II, with the exception that a minute quantity of the atmospheric air entering the tube 27, by way of the cut out 69, passes into the axial conduit 53, through the perforations 70, and thereby ensures a continuous supply to the pilot nipple 39. Furthermore, by provision of the means described to rotate the conduit 53 with the coordinate jet tips 40, and by forming said tips with divergent outlet flares, I impart a centrifugal fan-like action to the discharges therefrom and thereby accelerate the velocity of both fuel and its atomizing medium, with a consequential increased effectiveness of atomization and calorific efficiency.

When it is desirable that the atomizing agent be supplied to the burner 1 under pressure, and the fuel fed thereto with forced feed, I make use of the assemblage illustrated in Fig. VII, whereon all those parts previously described are designated by corresponding reference characters; while it

is to be noted that in this form of the invention I preferably employ a burner similar in type to that shown in Fig. III. In this case the drive shaft 71 of the motor 57 is, however, extended and journaled in bearings 72 secured on the lateral projection 58, and in addition to driving the belt 56 for rotating the conduit 53 it serves to directly drive a suitable compressor or blower 73. This compressor or blower 73 communicates by way of piping 74 with the atomizing medium connection 5 through interposition of a T 75 for coupling to another burner or burners 1, as will be readily understood by those acquainted with the art.

Mounted on the lateral projection 58 aforesaid, is an oil pump 76 having its discharge 77 communicating with the fuel feed connection 4, and said pump is—conveniently—operated by a belt drive 78 from the motor shaft 71. Gauge connections are designated on the drawings at 79, and attachment thereto of the requisite instruments will be obvious without further explanation herein.

The operation of this type of my invention conforms in all respects to that set forth in connection with Fig. III excepting that the fuel and its atomizing medium are, respectively, supplied under pressure and forced feed.

Attention is now directed to Figs. III and VII to the provision within the burner head 3 of a stuffing-box 80 that serves to effectively separate the fuel feed connection 4 from the atomizing medium connection 5; while apertures 81 in the tube 26 afford adequate communication into the clearance 35 intermediate said tube and the tube 27. Obviously, the compressed air connection 74 may be fitted with a control connection or branch 82—conventionally indicated by dotted lines in Fig. VII—communicating into the inner tube 27 and conduit 53, by way of an orifice 69', of the burner 1, so that high pressure air may be supplied to the pilot nipple 39 as well as to the several jet tips 40; in which event the pipe 27 will be non-rotatable.

Having described different forms and means for operating and varying the action of my novel burners 1, I will now briefly outline types of nozzles therefor which have been found highly efficient in use. Referring firstly to Figs. VIII and IX it is to be noted that I dispense with the several cupped nozzle pieces 28, 32 and 36 and clamp the tip-plate 30 directly to the end of the barrel 2 by means of the flanged lock collar 31; while the single orifice in said tip-plate is flared to provide an inclined face 83, with that in the flanged end of the lock collar 31 at substantially right angles thereto. On the other hand the intermediate pipe 26 is provided with a removable coned extension 85 having its outer end reversely beveled to afford inclined—outer and inner—edges 86, 87,

likewise at approximate right angles to one another. In similar manner the inner tube 27 is fitted with a removable end piece 88 flared to correspond in angularity to the inclined edge 87, or what may be conveniently designated a forty-five degree curvature 89, while the tip edge 90 may be reversely beveled at an angle of around ninety degrees thereto. Or, the respective angularities above 10 described may be variously arranged to afford other desired intersectional flow relations. From the foregoing it will be noted that, when the several parts just described are in the zero or substantially closed position 15 shown, the faces 83 and 86 parallel one another with the tip edge 90 medial relative thereto; whereas the curvature 89 and face 87 similarly parallel and intersect the above recited parallel faces 83, 86 at right angles. 20 To ensure accurate co-axial alignment of the pipes 26, 27, as well as to rigidly connect the same together, I fit the latter with an annular sleeve 91 having radial arms 92 snugly fitting the bore of the former, and retained 25 immovable by set screws 93.

Atomization of the fuel with the just described assemblage of burner nozzle, it will be apparent, is effected by what may be conveniently designated as right-angular shearing-action of circular intersecting flows of fuel and atomizer medium, over the edge 86 and intermediate the faces 87, 89, similarly directed into the combustion-supporting air, flaring the discharged by the end piece 88, 30 whereby a thoroughly vaporized combustible is obtained.

In Figs. X and XI I have illustrated a combination type of burner nozzle adapted to supply auxiliary gas to the super-atomized 40 combustible and thereby augment its calorific intensity. Fundamentally this type of nozzle embodies an annular channel 94, formed in the cupped member 28 with a service connection 95 from any convenient source of 45 gas—not shown. This annular channel 94, it is to be noted, is comparatively narrow, while the inner wall thereof is shortened at 96 relative to the outer wall so that the escaping gas is freely mixed with the liquid or 50 other combustible intermediate the tip-plate 30 and cap piece 33 on the inner cup member 32. On the other hand this annular channel 94 may be utilized as a return back-pressure line connection to a fuel pressure pump or its 55 equivalent. Attention is also directed to the outward flaring of the central portions of the tip plate 30 and paralleled end wall 97 of the cap piece 33, which jointly function to emit the escaping combustible and gas at a defi- 60 nitely predetermined angle to the atomizing agent flowing over the truncated removable tip 98, on the outer end of the inner tube 27. Conveniently the radial arms 92 of the sleeve or collar 91—in this form of my invention—65 frictionally fit into longitudinal grooves 99,

provided for their reception in the inner wall of the cup piece 32.

The operation of this form of burner nozzle substantially corresponds to that of the disclosure in Figs. VIII and IX, with the exception that auxiliary gas is commingled with the fuel flowing in film formation between the elements 30, 33, thereby ensuring a combustible mixture of correspondingly increased flame intensity. 75

Figs. XII and XIII illustrate a further form of burner nozzle differing but slightly from the type exemplified in Figs. II and III. In this form of my invention the pilot 80 nipple 39 is dispensed with and use made of three jet tips 100 which have their surrounding wall inclined outwardly with a flare of any desired degree, while their perimetric edges are formed with a bevel bead 101 of a

more acute angular section to give spread or distribution to the flame. In addition to the foregoing distinctions I fit the removable closure plate 102—of the cup piece 32—with tubular bushings 103, each having its bore tapered at 104 to correspond with that of the jet tips 100. In addition the outer free ends of the bushings 103 are coned at 105 in correspondence with the countersink portions 106 of the apertures in the tip plate 30 through which the jet tips 100 project, so that the fuel flowing through the clearance 34 is caused to follow an undulatory course and impinge the outer wall of said tips at an acute angle relative to the intersecting flow of atomizing medium passing through the clearance 35; all 90 as will be readily understood on examination of the drawings. 95

In Figs. XIV and XV I have shown a still further form of burner nozzle in which the pipes 26, 27 have their respective nozzle ends 107, 108 inwardly turned at substantially right—or other suitable—angles to their axes, so that the combustible flowing through the clearance 34 not only intersects the atomizing medium passing out of the inner pipe 27 at a correct angle for any given condition of fuel and other pertinent factors; but it also meets and combines with the combustion supporting core of atmospheric or high pressure air emitted by the conduit 53 thereby assuring instant ignition. 110

The operation of the types of burners shown in Figs. XII to XV, inclusive, are deemed so obvious from the previous operative explanations and the other types illustrated and described as not to necessitate further explanation herein. 115

It is desired to point out that by my invention variations in load and burner operation which require coincident and corresponding control in variation of fuel feed via the connection 4 and clearance 34, its atomizing medium supplied by the connection 5 and clearance 35, air supply to support combustion furnished by the pipe 27 and axial conduit 53, 125

and other features and functions incident to such operation, are all accomplished in an efficient manner. Further important distinguishing characteristics of this invention relate to the novel manner whereby air is supplied through the burner nozzle structures 1 by independent conduits 27, 53 for the "ignition" and "combustion-support" of the atomized fuel as discharged from the nozzle tip 30. The air conduits 27, 53 are not restricted as to cross-section but they function as controls for the atomized fuel streams at the point of discharge and consequently regulate and vary the intensity of the flame.

Also it will be noted that the design, formation of, and assembly of the various parts, their movement with respect to each other; including the means affording an axial columnar core and jet of combustion supporting atmospheric—or high pressure—air, are highly important factors in the operation of my improved burner. In fact they are of fundamental importance to the successful control of the flame intensity, while they also provide for the shaping, varying and regulation of the atomized fuel stream as it is discharged through—and from—the tip structure 30. In the embodiments disclosed the atomized fuel is discharged as a variable film, tubular in form, which surrounds a natural, automatically variable, pressure according to rate of operation, continuous core of atmospheric—or pressure—air; while all the said, respective, discharges of super-atomized combustible, atomizing mediums, and combustion-supporting air traverse each other at the exact point of discharge and ignition from the burner tip 30.

Finally the specific forms of my invention illustrated are by ways of examples only and are not to be restrictively regarded, as changes may be effected in their assembly, as well as other adaptations evolved, that will be fairly encompassed by reasonable interpretation according to the following claims.

Having thus described my invention, I claim:

1. Means for atomizing combustibles comprising coincidentally movable and relatively adjustable coaxial tubular members adapted to form variable burner outlets for intersecting discharge of fluent fuel and a suitable atomizing agent, and co-ordinate tubular means controlling a corresponding flow of combustion-supporting agent directly into the atomized discharge.

2. Means for atomizing combustibles comprising coincidentally movable and relatively adjustable coaxial tube members adapted to provide variable discharge burner outlets for flow of a fluent fuel and a fluid atomizing medium in direct intersecting tubular form relation, and a co-ordinate tube means controlling a commingling similar flow of atmospheric air across the atomized discharge.

3. In means for atomizing combustibles, the combination of coincidentally movable and relatively-adjustable coaxial tube members with means adapted to form variable discharge outlets for streams of a fluent fuel and streams of air under pressure which directly shear each other in a common zone of emission, and a coordinately movable tube controlling an accelerated flow of atmospheric air across the respective atomized discharges, whereby super-atomization of the commingled mixture is effected.

4. In means for atomizing combustibles, the combination of coincidentally movable and relatively-adjustable coaxial tubular members including outwardly flared jet tips and co-operative perforate plate elements jointly adapted to form tubular streams of a fluent fuel and similar streams of its atomizing agent that directly intersect each other, and an inner conduit adapted to direct an axial flow of combustion supporting air across the atomized tubular discharges to effect super-atomization.

5. In a burner for atomizing combustibles, the combination of coincidentally movable and relatively-adjustable coaxial tubes having perforate end closures with co-operative flared tips jointly adapted to form tubular discharges of a fluent fuel and its atomizing medium, means operative to rotate the flared tips, and means for adjusting the spacial relation of the flared tips and perforate closures to control and vary the intersecting flow of said fluent fuel and its atomizing medium.

6. In a burner for atomizing combustibles, the combination of coincidentally movable and relatively-adjustable coaxial tubes having perforate end closures and co-operative flared tips jointly adapted to form tubular discharges of a fluent fuel and its atomizing medium, gears operative to rotate the flared tips simultaneously, and means for axially moving said flared tips and one of the perforate closures relative to the other perforate closure to control intersecting shear and vary the respective supply of fluent fuel and its atomizing medium.

7. In a burner for atomizing combustibles, the combination of coincidentally movable and relatively-adjustable coaxial tubes having perforate end closures and co-operative flared tips jointly adapted to form tubular discharges of a fluent fuel and its atomizing medium, gears operative to rotate all of the flared tips simultaneously, associated eccentrics for adjusting the spacial relation of the flaring tips and one of the perforate closures relative to the other such element to control and vary intersecting shear of the fluent fuel and atomizing medium, and means effective to supply a variable flow of pressure air through each flaring tip.

8. In a burner for atomizing combustibles, the combination of coincidentally movable and

relatively-adjustable coaxial tubes having perforate end closures and co-operative flared tips adapted to form tubular discharges of a fluent fuel and its atomizing medium, gears operative to rotate all of the flared tips simultaneously, associated eccentrics for adjusting the spacial relation of the flaring tips and one of the perforate closures relative to the other to control and vary intersecting shear of the fluent fuel and atomizing medium, and conduit means effective to direct a flow of pressure air through each flaring tip; the aforesaid eccentric conduit means also jointly functioning to vary and control the tubular stream bulk, relative intersecting flow, and the atomized combustible discharge.

9. In a burner for atomizing combustibles, the combination of stationary and relatively-adjustable coaxial tubes having perforate end closures, co-operative flared tips adapted to form tubular discharges of a fluent fuel and its atomizing medium, intermeshing gear means operative to rotate the flared tips, means for adjusting the spacial relation of the flaring tips and one of the perforate end closures relative to the other to control and vary intersecting shear of the fluent fuel and atomizing medium, a coincidently adjustable coaxial tube adapted to direct a flow of pressure air exteriorly around each flaring tip, and a co-ordinate rotary axial conduit for supply of combustion supporting atmospheric air to the atomized combustible.

10. Apparatus for atomizing and burning fluent fuels comprising coaxial relatively-adjustable tubes having cupped outflow ends effective to emit tubular flows of the fuel and its atomizing medium, perforate closures at the outflow ends of said tubes with co-operative flared tips, and eccentric means whereby positional variations of the aforesaid flared tips and perforate elements may be effected to control the flow and intersectional cutting of the respective discharges.

45 11. Apparatus for atomizing and burning fluent fuels comprising coaxial coincidently-movable relatively-adjustable tubes having cupped outflow ends effective to discharge tubular flows of the fuel and its atomizing medium, perforate closures at the outflow ends with co-operative flared tips, gear means whereby the flared tips are rotatable, and relatively adjustable eccentrics whereby the tips and one or more of the aforesaid tubes 50 may be axially moved relative to another of the tubes to vary the angular outflow and intersection of the respective discharges.

12. Apparatus for atomizing and burning fluent fuels including coaxial coincidently-movable relatively-adjustable tubes having cupped outflow ends effective to discharge tubular flows of the fuel and its atomizing medium, perforate plate closures at the tube outlet ends with co-operative flared tips effective to converge the discharge flow and

control intersectional cutting of said fuel and atomizing medium, gears whereby the tips are rotated, co-ordinate relatively adjustable eccentrics whereby the tips and one or more of the aforesaid tubes may be axially moved relative to another of the tubes to varyingly form and control the bulk and intersecting flow of the fluent fuel and its atomizing medium, and means supplying combustion-supporting air for axial discharge through each flared tip.

13. Apparatus for atomizing and burning fluent fuels including coaxial coincidently-movable relatively-adjustable tubes having cupped outflow ends effective to discharge tubular flows of the fuel and its atomizing medium, perforate plate closures at the tube outlet ends with co-operative flared tips effective to converge the discharge flow and control intersectional cutting of said fuel and atomizing medium, an inwardly converged nipple located centrally of the flared tips serving as a pilot jet, gears whereby the tips and nipple are rotated, co-ordinate relatively adjustable eccentrics whereby the tips and one or more of the aforesaid tubes may be axially moved relative to another of the tubes to varyingly form and control the bulk and intersecting flow of the fluent fuel and its atomizing medium, and one of the tubes aforesaid with an extension conduit from the nipples serving to supply combustion-supporting air for axial discharge through each flared tip and the pilot jet.

In testimony whereof I have hereunto signed my name at Philadelphia, Pennsylvania, this 6th day of October, 1926.

FRANCIS H. BROWN.
